The ornamental design for an outdoor emergency power supply, as shown and described.

DESCRIPTION

FIG. 1 is a front and top perspective view of an outdoor emergency power supply, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated in FIG. 2. The broken lines in the figures illustrate portions of the outdoor emergency power supply that form no part of the claimed design. The dash dot dash lines in FIGS. 2 and 9 are for the purpose of depicting the cut line of the enlarged view and form no part of the claim.
